ABSTRACT OF THE DISCLOSURE

For installation on piers and the like, stair-like apparatus having at least two positions, one being retraction to a position preferably out of the water, and the other being a position extending into the water whereby a swimmer or boater has ease of access by the present invention and is permitted to climb to the pier with ease; said apparatus preferably including a pair of elongate members with a number of foot supporting members in between.

Summary of problem and invention

Numerous piers, wharves, and other erected or natural structures are adjacent bodies of water with the view of permitting loading and unloading of boats, vessels, and engaging in other maritime vehicles. In circumstances too numerous to tabulate, facilities are provided whereby individuals in the water or aboard small boats or vessels must climb to the top of the pier or wharf as a means of going on-shore. In most circumstances, the ladders are customarily in a sad state of repair or maintenance, and are therefore quite dangerous. The deterioration of wooden ladders near the water is an accepted fact and results from the chemical action of the water on the wood at the water line, and also the build-up of chemicals on the ladder from the water. For instance, pollutants and other impurities in the water will quickly coat the surfaces of the ladder and make it slippery or dangerous. Moreover, marine-life deposits typically coat the surfaces of most ladders. While some improvement in useful life is obtained by substituting metal ladders for wooden structures, this does not provide a final solution because marine deposits will also attach themselves to metal surfaces. Moreover, the slipperiness of a metal surface far exceeds that of a wooden surface, and increases dangers to the user.

It is with a view of the foregoing problems that the present invention is devised, and is hereby summarized as including an elongate means having a plurality of foot support means which is adapted to be positioned for access by a swimmer or other individual at the surface of the water. Moreover, the present invention is adapted to be positioned out of the water when not in use, and is so arranged and constructed on connector means to be pivoted from the position in the water and extending upwardly to the pier with pivotal movement to a stored position not exposed to the water. This substantially increases the life of the apparatus and further prevents fouling of the surfaces of the ladder to thereby permit its continued use for an indefinite period of time.

One object of the present invention is to provide a new and improved retractable ladder for installation on piers and the like which has at least two positions, one of which is in the water for convenience of a user and the other of which is retracted out of the water to prevent needless fouling of the ladder.

Another object of the present invention is to provide a new and improved climbing apparatus adapted to position and support a ladder in the water wherein the structural supports are independently mounted and aligned

2

free of the problems of pier settlement, misalignment of the pilings or the like.

Yet another object of the present invention is to provide a new and improved retractable ladder which is positioned either vertically or at an inclined angle for the convenience of the user.

An important object of the present invention is to provide a new and improved climbing apparatus suitable for installation on piers or wharves wherein the retracted position removes the ladder fully from the water to avoid exposure to the surface fouling resulting from being in the water and to further permit drying of the ladder to prolong the life of the apparatus.

Yet another object of the present invention is to provide a new and improved climbing apparatus suitable for installation on piers or the like permitting a substantial range of height for installation on a variety of structures.

An important object of the present invention is to provide a new and improved climbing apparatus which, in the retracted position, is out of the way of boats navigating near the pier to permit the boats to come along side for docking.

Other objects and advantages of the present invention will become more readily apparent from a consideration of the specification and drawings included wherein:

FIG. 1 is an isometric view of one embodiment of the present invention illustrating the climbing apparatus extending downwardly from a pier;

FIG. 2 is a sectional view taken along the center line of the structure shown in FIG. 1 in the retracted position;

FIG. 3 is a view similar to FIG. 2 showing the apparatus in the extended position;

FIG. 4 is an isometric view of an additional embodiment of the present invention;

FIG. 5 illustrates additional details of the structure shown in FIG. 4;

FIG. 6 is a side view of another embodiment of the present invention; and,

FIG. 7 is a sectional view taken along the line 7—7 of FIG. 6 illustrating means for positioning the lower end of the ladder in the water.

Attention is first directed to FIG. 1 of the drawings which illustrates in substantial detail the climbing apparatus of the present invention which is indicated by the numeral 10. The apparatus is adapted to be installed on a pier 12, the deck planing and major members being illustrated in the drawings with the vertical pilings omitted for clarity of illustration. The climbing apparatus 10 includes an elongate means 14 secured to and carried by a connector means indicated generally at 16, and adapted to be pivoted about an axis on the pier 12 from its stored, horizontal position to an inclined position extending downwardly toward the water. Moreover, a second connector means 18 is secured to the lower end of the climbing apparatus 14 to position the lower end in cooperation with the means 16. The apparatus 10 has two positions, one which is retracted and the other which is extended and useable with the lower end at or in the water. A plurality of steps is included in the ladder to enable any user, such as a swimmer, boater or other individual at the surface or in the water to climb the ladder to a position on the pier 12. Thereupon, the climbing apparatus 10 of the present invention is adapted to be retrieved onto the pier to thereby retract the lower end from exposure to the water and the damaging effects of the environmental conditions.

Considering the invention more in detail, the climbing apparatus 10 shown in FIG. 1 is secured to the pier 12. The structure 12 is of any desired founded construction and may be, by way of example, a pier, wharf, an off-

shore drilling platform, a fishing platform, or other erected structure at a body of water. The pilings have been omitted from FIG. 1 for purposes of clarity and to illustrate the fact that the present invention is not dependent on the pilings. This is of particular interest since pilings tend to settle in the sub-soil and become canted or inclined after an interval of time, and are therefore usually not reliable as a means of support for the present invention 10. Moreover, it is presumed that the pier 12 is generally horizontal and level within one or two degrees of the horizontal. Again, this is not a specific requirement of the present invention, although the climbing apparatus 10 is preferably used with a level structure, although it can be installed with a pier or other structure which is canted or inclined. Should the degree of settling of the pier 12 in the water be extreme, the apparatus 10 is preferably installed with the addition of necessary shim stock to adequately true the various members as will be described. Of course, these problems are noted in passing, and are of no consequence to the present invention.

The climbing apparatus 14 preferably includes a pair of parallel elongate members 20 and 21. A number of foot support means, preferably dowel rods 22 and 23, are included between the elongate rails or runners 20 and 21 at spaced intervals. The number of foot support means 22 is subject to variation; however, the spacing between support members is preferably regular to provide the expected foot supporting for an individual even when used in the dark. Moreover, the dowels 22 are preferably of substantial diameter to support the weight of the user and are anchored in the rails 20 and 21 in appropriately drilled holes at spaced locations.

In the example shown in the drawings, the rails 20 and 21 are perhaps six or eight feet in length. The pier 12 stands perhaps four feet above the water so that the lower foot support member 22 is positioned below the water in the extended position of FIG. 1.

The upper connector means 16 includes a mounting bracket 28 which is nailed or otherwise joined to the planking of the pier 12 and which has bifurcated tabs 29 and 30 extending upwardly from the deck of the pier 12. The spacing between the tabs 29 and 30 is such that the climbing apparatus 14 fits snugly between the tabs in the retracted position. Each of the tabs 29 and 30 has a central opening for a pivotal connection to each of a pair of elongate connecting rods 31 and 32, respectively. The connecting rods 31 and 32 extend from the tabs 29 and 30 to the upper end of the climbing means 14, and more particularly are pivotally joined to the rails 20 and 21 by the pin connectors 33 and 34. The connectors 33 and 34 pivot on rotation of the parallel rods 31 and 32 and the rails 20 and 21 of the climbing apparatus. Moreover, the connecting rods 31 and 32 are adapted to be rested on the planked deck of the pier 12 which serves as a stop means limiting the counter-clockwise rotation of the connecting rods to the position illustrated in FIG. 1.

With regard to the relative length of the various components, it will be appreciated that the connecting rods 31 and 32 are approximately one-half the length of the climbing means 14 between the connections of the upper and lower connector means 16 and 18, respectively. This fact is better illustrated in FIG. 2 which shows the upper connective means 16 fully rotated in a clockwise direction to the retracted position. Moreover, it will be noted in FIG. 2 that the means 16 is approximately one-half the length of the means 14 while yet providing a range of rotation approximately equal to the diameter of the circle of movement of the means 16. The location of the mounting bracket 28 on the pier 12 should be such that the movement to the left as shown in FIG. 2 carries the upper end of the climbing means 14 to a point beyond the pier 12 to avoid mechanical interference in the extended position.

While the foregoing describes the construction of the means 16, note should be taken of the lower connector

means 18 included in the structure. More particularly, a pair of mounting brackets 35 and 36 are secured by screws, nails or the like, to the face of the pier 12. The brackets 35 and 36 are preferably leveled by the use of the shim stock or other means accommodating vertical adjustment. In any event, the brackets are so positioned that the desired vertical alignment of the structure is maintained.

The bracket 35 supports a downwardly extended brace 37 which is parallel to a similar brace 38. The braces 37 and 38 are preferably parallel to a pair of braces 39 and 40. The braces 39 and 40 are secured to the pier 12, preferably by means of a transversely extending mounting bracket secured to the lower side of the pier 12 as shown in FIG. 2. Again, location of the braces 39 and 40 is assisted by the use of the shim stock, or other steps suggested herein to maintain the braces 39 and 40 parallel to the forward braces 37 and 38.

A pair of transversely extending support struts 41 and 42 is included in the structure, and each is connected to one of the brackets 35 and 36. The brace 39 and the strut 41 are joined to a gusset plate 43 which is symmetrical to a similar plate 44. The two plates are spaced from one another, and each provides a pivot for a connector rod 45 and 46. More particularly, the forward braces 37 and 38 extend downwardly to connection with rearwardly extending horizontal beams 47 and 48. The beams 47 and 48 also connect to the gusset plates 43 and 44, respectively. Rigidity of the frame structure described hereinabove is enhanced by the inclusion of a transversely extending lateral support 50 at the intersection of the braces 37 and 38 to the horizontal beams 47 and 48. It will be noted that a reinforcing gusset is provided at each intersection to enhance the rigidity of the corners.

From the foregoing, it will be noted that a stable structure is provided wherein an axis of rotation is centered in the gussets 43 and 44. Moreover, the means 18, serving as a pivotal connective means, is stabilized for rotation to the extended position of FIG. 1 or the retracted position of FIG. 2. In further particular, the length of the means 18 from the pivot point at its fixed end to the movable end connected with the ladder means 14 is such that the lower end of the ladder is movable from the extended position best shown in FIG. 3 to the stored position of FIG. 2. In the retracted position, the upper end is pivoted out of range of the water and upwardly to a position approximately parallel with and slightly above the pier 12. It will be noted in FIG. 2 that the approximate angle of rotation from the horizontal to the inclined and retracted position is on the order of sixty or seventy degrees of rotation. Of course, this can vary with different installations and is not a limitation on the apparatus of the present invention. Further, it will be noted that support of the apparatus is independent of the piling 51 shown in FIGS. 2 and 3, which, as noted, is subject to settling and misalignment.

The apparatus shown in FIGS. 1-3, inclusive, should be considered from the point of view of its operation, and more particularly with focus directed to the cleanliness and unlimited life of the climbing apparatus. In FIG. 1, the apparatus is shown with the ladder means 14 extended toward the surface of the water. As previously noted, the ladder means may be extended only to the surface or into the water, depending on its requirements. For instance, should the device be used by a swimmer, it is preferable to position one or two steps beneath the water so the swimmer has little difficulty in elevating himself from the water when lacking firm support. Moreover, should the apparatus 10 be desired for small boats or other vessels having nominal freeboard, the means 10 preferably extends to the surface of the water with the lowermost rung or foot support 22 positioned immediately at a convenient level.

Viewing the structure as illustrated in FIG. 2, it will be noted that the climbing apparatus 14 is fully retracted

from the water. As a matter of fact, the means 14 is only slightly exposed to the water spray and is certainly not subject to build-up deposits or decay. More particularly, the apparatus remains unexposed when not in use. Only at the time of use is the present invention exposed to the degenerating effects of the water; however, retraction permits the surfaces to dry in combatting the rotting and decay of the equipment. By way of contrast, it is not uncommon for oil slime or other pollutants in the water to form a residue on the climbing apparatus 10.

The embodiment 10 is illustrated in FIG. 2 in the fully retracted position. More specifically, the upper connector means 16 is rotated to its right hand extremity of movement as illustrated in the drawings. In further particular, the means 18 is rotated in the clockwise direction toward the vertical. As illustrated in the drawings, the means 18 swing upwardly between the brackets 35 and 36 to nearly contact the lower side of the pier 12. In this posture, it will be appreciated that the climbing apparatus is secured on the pier 12 and substantially out of the water. Moreover, drying of the surfaces of the climbing apparatus is permitted. Even if the surf should be excessively rough and often covers the pier 12, even still, the means 14 is maintained high and dry above the water during its unlimited life.

The dotted line representation of FIG. 2 illustrates the embodiment 10 of the present invention during rotation from the fully retracted position to the extended posture. In the movement of the means 14 to the extended position, each of the connector means 16 and 18 is rotated about its respective pivot point. While the angles of rotation differ, this is in part caused by the differences in length of the means 16 and 18 and is of no particular consequence.

In FIG. 3, the climbing apparatus 14 is fully extended from the pier 12. It will be noted that the upper connector means is rotated and contacts the pier 12 which serves as a stop means. Also, the transverse brace 50 shown in FIG. 1 serves as a stop mean for the lower connector means 18 if desired. If desired, the extended means 14 is enhanced by addition of support rungs below the connector means 18 which extend even further into the water. It will be appreciated that such an appendage is well within the scope of the present invention.

Attention is next directed to FIG. 4 of the drawings which illustrates an alternative structure indicated by the numeral 60. The apparatus 60 includes an upper connective means 61 secured to the deck of a pier 62. A lower connective means 63 is joined to a climbing means 64. The lower connective means is supported and braced by appropriate framing indicated generally at 65.

The upper connective means 61 includes a pair of elongate members 67 and 68 which are pivotally secured by appropriate hinges to the pier 62. Each of the means 67 and 68 has hinged connectors at the movable ends for pivoting the climbing apparatus 64. The climbing means 64 includes a pair of elongate members 69 and 70 between which a number of steps or foot support means 71 and 72 are secured. By way of contrast, the steps 71 and 72 present flat upper surfaces when compared with the dowel rods 22 and 23 illustrated in FIG. 1. This simply illustrates one variation of the present invention.

The support means 65 is somewhat similar to the supporting structure illustrated in FIG. 1 in function to position a shaft 74 beneath the pier 62 for a pivot point for the lower connector means 63. The framing 65 preferably takes the form of an inverted A-frame secured to the under side of the pier 62. As was the case for the embodiment 10, shim stock or other appropriate means is used to level and align the framing 65 to level the shaft 74. As was the case in the embodiment 10 also, the pilings are preferably not used with the structure of the present invention since they tend to settle and would possibly misalign the present invention. Of course, if the pilings are properly set in the subsoil, they may very

well be used as supporting structure for the present invention. However, this choice is left to one installing the present invention.

Particular emphasis is directed to the lower connective means 63. It will be noted that the shaft 74 is the pivot point. The means 63 includes a pair of L-shaped angle iron members 76 and 77 which pivot about the shaft 74. Each of the members 76 is L-shaped whereby the shaft 74 is positioned substantially above the lower end of the climbing apparatus 64 which extends downwardly into the water. This serves as one means of elevating the pivot means above the water. This is of assistance in maintaining a generally frictionless pivot connection above the surface of the water although this is not required for operation of the present invention. For structural rigidity, the members 76 and 77 are preferably formed of angle iron stock or other reasonably stout fabricating material. Preferably the members 76 and 77 extend vertically upwardly as a result of the off-set to avoid possible interference with the vertical sides of the pier. This avoids the necessity of cutting into the framework of the pier.

The use of angle iron stock is preferably extended to the components of the structural framing 65. Of particular interest is the upright members 78 and 79, joined to the pier at a notched opening 62a of the pier 62. The notched opening serves several purposes. In the first instance, the planking is preferably notched to provide a suitable anchor for the members 78 and 79 at the upper ends. Moreover, the width of the notch, after installation of the members 78 and 79, is preferably slightly greater than the width of the climbing means 64 which is positioned in the notch as shown in FIG. 4. A clamping action on the sides of the members 69 and 70 provides lateral stability to the present invention. Moreover, the notched portion need not be snug against the members 69 and 70 to substantially strengthen the present invention when installed.

In operation, the embodiment 60 is used somewhat in the same manner of the embodiment 10. It has a retracted position wherein the means 61 is rotated clockwise to the extremity of movement to retract the climbing means 64 from the water. Concurrent with rotation of the means 61 is rotation of the lower means 63. The means 63 rotates about the shaft 64 to lift the lower end of the ladder 64 from the water. As previously described, a sizeable portion of the lower connector means 63 is above the surface of the water.

Of interest to the present invention is the relative dimensions of the members 76 and 77 in relation to the axis 74. Since the shaft 74 is set back of the notch 62a in the pier, the generally horizontal arm of the members 76 and 77 is preferably slightly longer than the distance of the set-back. Also, the same arm is preferably slightly longer than the vertical distance from the shaft 74 to the top of the pier 62. On achieving these preferred lengths, the arms 76 and 77 then permit the lower end of the climbing apparatus 64 to be retracted to the pier 62, centered within the notched portion 62a. The angle of the structure 60 is approximately equal to that of the structure 10 previously described. In both instances, it will be noted that the ladders extend at approximately thirty degrees with respect to the vertical.

Attention is next directed to FIG. 6 of the drawings which illustrates even a third embodiment of the present invention. The structure includes an upper connective means 91 secured to a climbing apparatus 92. The climbing apparatus cooperates with a lower connector means 93 as will be described. The lower connector apparatus 93 cooperates with a structural framing means 94 which is somewhat similar to the inverted A-frame 65 described above. The structural support means 94 is appended to the lower side of the pier 95 in the same manner as previously discussed.

Of particular interest to the structure shown in FIG. 6 is the fact that the climbing apparatus is held in a vertical position when extended toward the water. On the other hand, the retracted position remains the same, essentially horizontal on the pier 95. The upper connective means 91 functions in the same manner as that described hereinbefore. More particularly, it is preferably anchored on the deck of the pier 95 and includes means permitting its rotation through approximately one hundred eighty degrees to extend to the left or the right as viewed in FIG. 6. Again, the connector means 91 is approximately one-half the length of the climbing apparatus 92 so that a substantial portion, or even the entire length of the ladder is retracted to the deck and positioned thereon. It is of note that the lower portions of the ladder means 92 may extend beyond the forward edge of the platform or pier is needed. At any event, the means 91 is described herein as being essentially similar in construction and function to the means discussed above.

The climbing apparatus 92 is preferably similar or identical to previously discussed structures. More specifically, it includes a pair of parallel members with a number of steps positioned therebetween. The steps may be metal or the round wooden dowels shown in FIG. 1 or can provide the flat upper surfaces somewhat as shown in FIG. 4. It should be noted that each of the steps 71 and 72 in FIG. 4 are positioned at an angle with respect to the elongate members 69 and 70 to provide a horizontal plane when used. The differences in the angle of the ladders accounts for the slight canting of the steps shown in FIG. 4 with respect to the ladder apparatus 64. For use in the embodiment 90, the steps are perpendicular and the climbing apparatus is conventional in construction.

The structural support means 94 is substantially constructed along the lines discussed with regard to the support means 64. That is, it includes a pair of preferably spaced, aligned, inverted A-frames secured beneath the pier 95, being joined thereto to provide true vertical alignment of the structure. The means 94 supports the lower connector means 93 as will be discussed hereinafter.

Attention is directed to FIG. 7 which illustrates details of the means 93. The structural means 94 includes a preferably vertical member 96 (preferably of angle stock). Since the means 94 is symmetrical on the right and left, it will be appreciated that two vertical members are spaced from one another to guide and seat the ladder means 92 when it is positioned in the water. The ladder means 92 incorporates a pair of elongate members 97 as shown in FIG. 7. In the present embodiment, the member 97 is constructed of angle stock and is shown nested and aligned within the vertical member 96 as a means of gaining lateral stability.

The vertical member 97 extends the full length of the climbing apparatus 92 to support the foot supports for the user. The lowermost rung is indicated at 98 and is joined to the vertical member 97 by means of a rivet, spot weld, or other appropriate joining means. Beneath the lowermost rung 98, a notch or cut-out 97a shapes the lower end of the climbing apparatus 92 for locking in place. A locking post 99 is joined to the means 96 and extends perpendicular to the plane of FIG. 7 for locking engagement with the notch or cut-out 97a. Since the embodiment 90 has symmetrical counterparts on both sides of the climbing apparatus 92, it will be understood that the lower end is locked in position. That is, lateral movement of the lower end is limited, because the vertical load on the ladder sets the notch 97a on the locking pins 99 which clamp the members 97 against the members 96. More particularly, the means 93 should be considered in operation. It will be observed from the dotted line representation of FIG. 6 that the lower end of the climbing apparatus 92 swings in an arc to the illustrated position. The arcuate seating of the lower end is accommodated

5 by the open front or face of the means 99 cooperative with the upright member 96, which, so to speak, sheaths the lower portions of the climbing apparatus 92, it being understood that the lower end is essentially inserted into the space between the locking pin 99 and the upstanding flange of the vertical member 96. The insertion is accomplished in the arcuate movement of the climbing apparatus 92.

10 In operation, movement of the climbing apparatus 92 from the retracted position is achieved by lifting the end of the ladder from the platform or pier 95 and rotating it to the illustrated position of FIG. 6. The arcuate movement of the climbing apparatus at its lower end brings the lower end into engagement with the lower connective means 93. Guidance is obtained by the tendency of the upright member 96 to true the ladder 92 during movement by abutting the flanges. The ladder is secured in position with the lower end made fast, the central portion captured between the flanges of the structural support means 94, and with the upper portion held by the upper connector means 91.

20 Of particular interest is the fact that the climbing means 92 is essentially vertical when compared with the structures 60 and 10 described above. It is of no particular consequence what angle is assumed by the structure 25 when erected; this can be varied depending on the requirements of installation.

25 Note should be taken of several general factors 30 effecting the use of the present invention. Little has been said concerning the length or dimensions of the climbing apparatus provided by the present invention. This is subject to a wide range of variation; some piers are merely two or three feet above the water while others are perhaps twenty or thirty feet removed from the surface.

35 Moreover, the width of each ladder is preferably on the order of two feet, although this may easily be altered to substantial widths as desired. The structural materials 40 are subject to a wide range of variation and include treated and untreated wood, galvanized metals, and others. Moreover, the means of fabrication is subject to the choice of material wherein wooden structures are preferably pre-cut to join one another and are either glued or bolted together. Metallic structures are preferably joined by means of bolts, rivets, spot welding, or the like.

45 Alterations can be included with the present invention, such as the addition of hand rails to the embodiment 60 shown in FIG. 4. One or two hand rails positioned above and parallel to the elongate members 69 and 70 assist the user in emerging from the water. If the hand rails extend from the climbing apparatus 64 by a distance of perhaps one or two feet, substantial assistance is lent to the user to enable him to steady himself as he climbs the apparatus. Moreover, the hand rails have no effect on the operation of the present invention, either in the retracted position or in the extended position.

50 While the foregoing describes the preferred embodiments of the present invention, the scope of the present invention is preferably defined by the claims appended hereto.

55 What is claimed is:

1. Climbing apparatus for installation on piers and the like to permit a person to ascend from or descend toward water, comprising:
  - (a) an elongate means of predetermined length;
  - (b) a plurality of foot support means spaced along said elongate means and adapted to support the weight of a user;
  - (c) connector means adapted to secure said elongate means relative to the pier;
  - (d) said connector means including:
    - (1) a pivotal connection;
    - (2) structural support means adapted to be located beneath the pier for supporting said pivotal connection;
    - (3) an elongate member extending from said

pivotal connection, said member connected to said elongate means near the lower end thereof for support and having a range of movement from the retracted position to a position with the lower end of said elongate means in the water; and

(4) said connector means securing said elongate means in an essentially retracted position withdrawn from the water, and said means also securing said elongate means in near proximity to the water for use by a person in ascending from or descending toward the water.

2. Climbing apparatus for installation on piers and the like to permit a person to ascend from or descend toward water, comprising:

- (a) an elongate means of predetermined length;
- (b) a plurality of foot support means spaced along said elongate means and adapted to support the weight of a user;
- (c) structural support means adapted to be positioned beneath the pier;
- (d) pivotal connection means supported by said structural support means;
- (e) an elongate member extending downwardly and at an angle from said pivotal connection means and into the water for supporting the lower portion of said elongate means; and
- (f) said pivotal connection being located above the surface of the water and said elongate member having a retracted position above the surface of the water.

3. The invention of claim 2 wherein said elongate means includes a pair of essentially parallel members with said foot support means joined to said parallel members.

4. The invention of claim 2 wherein said pivotal connection means is adapted to be secured to the pier at a location such that the retracted position of said elongate means is essentially horizontal.

5. The invention of claim 2 wherein said pivotal connection means is adapted to be secured to the pier at a location such that the retracted position of said elongate means is essentially shielded from the water by the pier.

6. The invention of claim 2 wherein said pivotal connection means is adapted to be connected adjacent an upper surface of the pier and including means for limit-

ing movement of said elongate means past the retracted position.

7. The invention of claim 2 wherein said pivotal connection means is adapted to be connected adjacent an upper surface of the pier and extends essentially on the upper surface of the pier for support, and extends toward the edge of the pier above the water for positioning said elongate means between the pier and above the surface of the water.

8. The invention of claim 2 wherein said pivotal connector means is approximately half the length of the portion of said elongate means resting on the pier in the retracted position; and wherein movement of said connector means in changing position of said elongate means moves said elongate means from a generally vertical attitude to a generally horizontal attitude.

9. The invention of claim 2 including:

- (a) structural support means adapted to be positioned beneath the pier;
- (b) a pivotal connection supported by said structural support means;
- (c) an elongate member extending downwardly and at an angle from said pivotal connection and into the water for supporting the lower portion of said elongate means; and
- (d) said pivotal connection being located above the surface of the water and said elongate member having a retracted position above the surface of the water.

10. The invention of claim 2 including means for stabilizing said elongate means in place and against a lateral movement when said elongate means is in near proximity to the water.
